UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

METHOD FOR BIFURCATING BLANKS.

1,424,540.

Specification of Letters Patent. Patented Aug. 1, 1922.

Application filed February 12, 1920. Serial No. 358,015.

To all whom it may concern:

Be it known that I, RICHARD LESTER WILCOX, a citizen of the United States, residing at Waterbury, in the county of New Haven 5 and State of Connecticut, have invented certain new and useful Improvements in Methods for Bifurcating Blanks, of which the following is a specification, reference being had therein to the accompanying drawings.

My invention has particular reference to a new and improved method for bifurcating blanks, the bifurcation being accomplished by slotting the shank of the blank, which 15 when completed has walls that taper toward each other as they approach the head of the blank.

The object of my invention, among other things, is to make the cuts with tools, that 20 so far as possible are of standard size and shape and readily procurable in the open market, and with the minimum number of specially prepared tools, and these so designed as to be economically constructed and 25 capable of standing the maximum strain and wear.

To these and other ends, my invention consists in a method for bifurcating blanks substantially as shown herein and illustrated 30 in the accompanying drawings, wherein:

Figure 1 is a view of the blank after the completion of the first operation thereon;

Figure 2 is a view of the same blank after the completion of a subsequent operation 35 thereon;

Figure 3 is a view of the same blank after the completion of a still later operation in the series; and

Figure 4 is an illustration of the completed bifurcated blank.

In the drawings, I have illustrated the blank as having a round head but desire it to be understood that the size and shape of the head is entirely immaterial to my invention, in fact it is immaterial whether the blank be provided with a head or nut. The 45 slot in the blank is herein shown as terminating adjacent to the underside of the head, but it may terminate at a point distant therefrom, if so desired.

In the drawings the blank shown has a shank 10 and a head 11. The first step in the practice of my invention and improved method consists in cutting the slot 12 in the 55 end of the shank by a cutter which I have

shown by broken lines and designated by the numeral 13, this slot preferably being substantially the same width as the finished slot at the bottom thereof.

The second slot 15 is now made in the 60 blank as an extension of the slot 12 and of the same width thereof, by a cutter 14 of the same standard type and shape as the cutter 13. Subsequently the slot 15 is extended to produce the slot 16 which is formed by the 65 cutter 17 of the same general shape as the cutters 13 and 14. The shank now has a slot of substantially uniform width extending from the end of the blank to a point adjacent to the head and formed, as shown herein, by three cutters which are of standard size and shape and readily procurable in the open market. These several cuts 12, 15 and 16 may be made with the same cutter, if desired, instead of three cutters as herein 70 shown. The desirability of having three cutters, instead of one, being to reduce the wear and strain upon each of the cutters and while I have shown three of these slots in the series, a greater or less number may be 75 made as may be desired, this depending upon the tools, length of the blank, etc., but for all practical purposes, three are sufficient.

The final and last cut is made with a cutter 18 having teeth 19 thereon of the same shape 85 in cross section on the cutting edge as the finished slot 20. This cutter is passed through the slot 16, substantially as shown in Figure 4, removing the stock from the sides of the slot and truing up the same to 90 complete the finished slot. The cutter 18 is specially designed, but the teeth 19 are of such size as will stand the maximum strain and have the minimum amount of work to do, in fact the limited volume of material 95 to be removed by this cutter is nothing more than a substantially truing up and shaping the walls of the already cut slot.

Having described my invention what I claim as new and desire to secure by Letters 100 Patent is:

1. The method for bifurcating blanks comprising the slotting of the blank with one or more cuts of substantially uniform width in alignment with each other and substantially parallel to the length of the blank, then cutting the sides of the said cuts to form the sides of the finished slot.

2. The method for bifurcating blanks consisting in slotting the blank with one or 110

more cuts of substantially equal width in alignment with each other and substantially parallel with the length of the blank, the width of one of said cuts being substantially 5 the same as that of the finished slot at the narrowest point thereof, and then cutting the sides of the said cuts to form the sides of the finished slot having converging walls.

3. The method for bifurcating blanks consisting in slotting the blank with cuts of substantially equal width in alignment with each other, thereby producing a slot with substantially parallel sides and then cutting both sides of said slot so as to produce a 10 finished slot, the walls of which taper on both sides thereof toward each other as they approach one end of the slot.

4. The method for bifurcating blanks

with a slot having converging walls, consisting in first cutting from the blank so 20 much thereof as is in the substantially longitudinal center of said slot, the walls of said cut portion being substantially parallel with each other, and then removing from the walls of said cut portion so much thereof as 25 is necessary to produce the finished slot.

5. The method of bifurcating blanks comprising the slotting of the blank with one or more cuts in alignment with each other and then cutting the blank adjacent to the aforesaid cut so as to form the sides of the finished slot.

In testimony whereof, I have hereunto affixed my signature.

RICHARD LESTER WILCOX.
